(57) CLAIM

The ornamental design for a hot gas volatizing device, as shown and described.

DESCRIPTION

FIG. 1 is a front elevational view, of our new hot gas volatizing device

FIG. 2 is a right view thereof,

FIG. 3 is a top view thereof,

FIG. 4 is a left view thereof,

FIG. 5 is a back view thereof,

FIG. 6 is a bottom view thereof,

FIG. 7 is a perspective view thereof,

FIG. 8 is a perspective view thereof,

FIG. 9 is a perspective view thereof; and,

FIG. 10 is a perspective view thereof.

1 Claim, 10 Drawing Sheets

FIG 1.

FIG 2.

FIG 3.

FIG 4.

FIG 5.

FIG 6.

FIG 7.

FIG 8.

FIG 9.

FIG 10.
